UNITED STATES PATENT OFFICE.

MICHAEL COLWELL MULLARKY, OF MONTREAL, QUEBEC, CANADA, ASSIGNOR TO AMES HOLDEN McCREADY, LIMITED, OF MONTREAL, CANADA, A CORPORATION.

SKATING-BOOT.

1,261,152.

Specification of Letters Patent. Patented Apr. 2, 1918.

Application filed May 8, 1916. Serial No. 96,068.

To all whom it may concern:

Be it known that I, MICHAEL COLWELL MULLARKY, a subject of the King of Great Britain, and resident of the city of Montreal, Province of Quebec, Canada, have invented certain new and useful Improvements in Skating-Boots, and do hereby declare the following to be a full, clear, and exact description of same.

10 This invention relates to a boot, for instance a skating boot having an ankle support therein and appertains particularly to the fastening means of such ankle support, the object of the invention being to provide 15 a simplified ankle support securing means whereby both sides of the support can be positively secured about the ankle of the wearer by a single strap and without bulky doubling of the strap.

20 For full comprehension, however, of my invention reference should be had to the accompanying drawings forming a part of this specification in which similar reference characters indicate the same parts and 25 wherein:

Figure 1 is a perspective of a boot constructed according to my invention; and

Fig. 2 is a perspective partly in section through the boot upper and ankle support 30 and taken just above the strap for fastening the latter.

Referring now to the drawings 2 indicates the upper of a skating boot provided with the usual eyelets 3 for lacing, the tongue 35 being shown at 4.

Within and extending forwardly from the back of the boot is an ankle support 5 which extends upwardly preferably from a point near the bottom of the boot and is stitched 40 to the back of the upper and along the sides near the bottom, the front sides or margins being free to be snugly bound about the ankle of the wearer.

The ankle support is fastened by adjustable means independent of the lacing of the boot upper, the fastening shown consisting of a strap 6 sewed or otherwise permanently fastened at 7 to one free margin of the ankle support at one side of the boot and a device 50 inside the boot upper for positively fastening the strap to the other margin, such device preferably consisting of a buckle 8 secured to said other free margin of the ankle support at the opposite side of the boot. 55 The stitching 7 is carried through tongue 4

and serves to fasten adjacent margins of ankle support and tongue together.

When the wearer's foot is inserted into the boot the free end of the strap 6 is passed through the buckle and the two sides of the 60 ankle support drawn toward each other and bound snugly about the ankle, the strap and buckle being held together and both free sides of the support positively secured against loosening by catching the tooth 9 of 65 the buckle through one of the holes 10 of the strap. After passing through the buckle and being fastened, the strap if lengthy may be conveniently accommodated by passing same freely on in the same direction, that is 70 toward the opposite side of the boot to that upon which is located the ankle support margin to which the strap is permanently secured and inserting the strap outwardly through a slot 11 in the boot upper on such 75 opposite side and if desired the free end of the strap may be slipped loosely under a keeper 12 upon the outside of the boot upper and adjacent the slot therein.

To enable the strap to be readily engaged 80 with the buckle, the latter is secured to the ankle support in a position with the frame projecting outwardly slightly beyond the front edge of that side of the support to which it is secured so that such edge of the 85 support does not interfere with the passing of the strap through the frame of the buckle.

From the above it will be seen that the strap and buckle positively secure both margins of the ankle support without the formation of bulky bends or turns of the strap and furthermore as the engaging strap and buckle are both within the boot upper, the ankle support can be properly fastened independently of the boot upper and before 95 the latter is laced.

What I claim is as follows:

1. The combination in a boot, of an ankle support within the boot extending upwardly 100 from near the bottom thereof and from the rear to the front at both sides of the boot in a manner substantially coincident and coextensive with the boot upper, and means for fastening the ankle support about the 105 ankle of the wearer, such means consisting of a strap and a buckle located inside the boot upper.

2. The combination in a boot, of an ankle support within the boot having two margins 110

adapted to be bound about the ankle of the wearer, such margins extending upwardly from near the bottom of the boot and from the rear to the front on opposite sides of the boot in a manner substantially coincident and coextensive with the boot upper, a buckle secured to one margin of the ankle support and a strap secured to the other margin of the ankle support and adapted to be engaged with the buckle.

3. The combination in a boot, of an upper having a slot therein at one side, an ankle support within the boot having a free margin at each side of the boot and adapted to be bound about the ankle of the wearer, such margins extending upwardly from near the bottom of the boot and from the rear to the front on opposite sides of the boot in a manner substantially coincident and coextensive with the boot upper, a buckle secured to that margin at the slotted side of the boot and a strap secured at one end to the other margin, adapted to be engaged with the buckle and passed outwardly through said slot in the boot upper.

4. The combination in a boot, of an ankle support within the boot, extending upwardly from near the bottom thereof and from the rear to the front at both sides of the boot in a manner substantially coincident and coextensive with the boot upper, and means for fastening the ankle support about the ankle of the wearer, such means consisting

of a strap secured at one end to one side of the ankle support and a device for positively fastening the opposite end of the strap to the other side of the support, such fastening device being located inside the boot upper.

5. The combination in a boot, of an ankle support within the boot having two margins adapted to be bound about the ankle of the wearer, a tongue in the boot having one side margin secured to one margin of the ankle support, a buckle secured to one margin of the ankle support and a strap secured to the opposite margin of the ankle support and adapted to be engaged with the buckle.

6. The combination in a boot open at the front and provided with the ordinary fastening means for closing same, of a tongue at the front of the boot and inside the closable front, an ankle support within the boot having two margins adapted to overlap the outside of the side margins of the tongue, and means for fastening the side margins of the ankle support which overlap the tongue, about the ankle of the wearer, such means consisting of a buckle secured to one overlapping margin of the ankle support and a strap secured to the other overlapping margin of the ankle support.

In testimony whereof, I have signed my name to this specification.

MICHAEL COLWELL MULLARKY.
